CLAIM

The ornamental design for a display screen with virtual three-dimensional shoe icon or display system with virtual three-dimensional shoe icon as shown and described.

DESCRIPTION

FIG. 1 is a front view of a display screen with virtual three-dimensional shoe icon in which the icon is shown in a side orientation;

FIG. 2 is another front view thereof, showing a front perspective orientation thereof;

FIG. 3 is another front view thereof, showing a front orientation thereof;

FIG. 4 is another front view thereof, showing an opposite side front perspective view of the shoe;

FIG. 5 is another front view thereof, showing a side orientation thereof;

FIG. 6 is a front view of a display system with virtual three-dimensional shoe icon shown in a side view, the virtual three-dimensional shoe icon being the same design as shown in FIGS. 1-5;

FIG. 7 is another front view thereof, showing a front perspective orientation thereof;

FIG. 8 is another front view thereof, showing a front orientation thereof;

FIG. 9 is another front view thereof, showing an opposite side front perspective orientation thereof; and,

FIG. 10 is another front view thereof, showing a side orientation thereof.

The uneven-length broken lines immediately adjacent to the shaded area in FIGS. 1-2, 4-7, and 9-10 define the bounds of the claimed design and form no part thereof. The uneven-length broken lines depicting the remainder of the shoe icon form no part of the claimed design. In FIGS. 1-5, the outermost even-length broken line represents a display screen which forms no part of the claimed design. In FIGS. 6-10, the outermost even-length broken line represents a portion of a field of view for a visual display and forms no part of the claimed design. The icon in FIGS. 1-10 is shown in various orientations to provide an understanding of the three-dimensional appearance of the design.
